(57) **CLAIM**

The ornamental design for a portable water filtering system, as shown and described.

DESCRIPTION

FIG. 1. Is a front elevational view of a portable water filtering system showing my new design;

FIG. 2. Is a rear elevational view thereof;

FIG. 3. is a side view thereof;

FIG. 4. is a opposite side view thereof;

FIG. 5. Is a top view thereof, and,

FIG. 6. Is a bottom view thereof.
